MEANS FOR RECORDING TELEPHONIC MESSAGES

Benjamin Silvermaster, Tacoma, Wash.

Application December 18, 1945, Serial No. 635,827

15 Claims. (Cl. 179—5.5)

(Granted under the act of March 3, 1883, as amended April 30, 1928; 370 O. G. 757)

1

The invention described herein may be manufactured and used by or for the Government for governmental purposes, without the payment of any royalty thereon.

The subject invention concerns a system for recording telephonic messages at the called telephone in the absence of any attendant at such telephone.

The recording is accomplished through the use at the called telephone of means which are not responsive to the normal ringing current supplied to the called telephone but are responsive to a modification in the character of the ringing current. Upon such modification, the recording means may be introduced into the circuit at the discretion of the calling party in order that a message which such party wants to leave at the called telephone may be recorded.

The drawing shows the system arrangement.

The calling telephone 10 and the called telephone 23 are both conventional instruments. Calling telephone 10 includes a dial 11. Lines 12 and 13 are conventional lines connecting calling telephone 10 with central exchange 14. Similarly, the called telephone 23 is connected to central exchange 14, on one side through conventional lines 22 and 84, and on the other side, when switch 25 is on contact 37, through lines 21 and 24. Central exchange 14 includes a conventional ringing generator 16 which is located in circuit 15 and which, by closing switch 17, may be put into operation to supply normal ringing current to lines 21 and 22. Central exchange 14 also includes a ringing generator 19 which is located in circuit 18 and which may be put into operation by closing switch 20, to cause a modification of the character of the ringing current supplied to lines 21 and 22. In place of a separate ringing generator 19, however, the character of the ringing current produced by ringing generator 16 itself may be modified.

When switch 25 is closed on contact 37, the operation of the called telephone 23 in the usual manner will be possible. However, when switch 25 is connected with contact 36, the recording means are in position to operate. Normally-open relay 28 is connected on one side to line 21, through conductors 29 and 30, contact 36 and switch 25, and on the other side to line 22, through conductor 31, condenser 32 and conductor 35. In conductor 26, which connects with line 81, one side of the power supply circuit, there is a contact 38 in position to be connected with switch 33 upon operation of relay 28. Spring 34 holds switch 33 in normally open position. Switch 33 is connected through conductor 39 to one side of motor 40. The other side of motor 40 is connected through conductor 27 to line 82, which is the other side of the power supply circuit.

2

Motor 40 is connected by means of shaft 41 to gear 43 which is part of a train of gears including also gears 42, 44, and 45. Attached to gear 42 is a dog 83 which is designed to cause switch 49 to engage contact 50 when the gear train has moved a predetermined distance. Attached to gear 44 is a spring 46 intended to return the gear train to its original position when there is no current flowing through motor 40. Attached to gear 45 is a governor 47 intended to regulate the rate of return of the gear train to its original position.

Relay 65 is also of the normally open type, being held in such position by spring 62, which is attached to the multi-sectional switch arm 58. Switch arm 58 includes conducting portions 55, 56 and 57, and insulating portions 59, 60 and 61. Conducting portion 55 is connected through lead 63 to conductors 51 and 64. Conductor 51 is connected to switch 49, and conductor 64 to one side of relay 65. Conducting portion 56 is connected through conductor 72 to line 81. Conducting portion 57 is connected through conductor 73 to conductors 29 and 30. In position to be contacted by switch arm 58 when the relay is operated, are contacts 52, 53, and 54. Contact 52 is connected through conductor 71 to conductors 70 and 48. Contacts 53 and 54 are connected to conductors 77 and 78, respectively. The other side of relay 65 is connected through conductor 66 to one side of battery 67, the other side of which is connected to conductor 68.

It would, of course, be possible to use a single source of power in place of the two sources consisting of the power supply circuit including lines 81 and 82, and of the battery 67.

Recorder 74 is in general of a conventional type including a motor 75, a recorder head 76, and conventional means for changing the record. Recorder 74 includes also normally-closed switch 69 which is momentarily opened upon completion of recording of a message, and which is connected through conductor 70 to conductors 48 and 71. Contact 85 designed to be engaged by switch 69 is connected to conductor 68. Motor 75 is connected on one side through conductor 80 to line 82, and on the other side to conductor 77. Recorder head 76 is connected with conductors 78 and 79.

The method of operation of the system is as follows:

Let it be assumed that switch 25 is engaged with contact 37. In this situation the functioning of the telephone system is thoroughly conventional.

However, if switch 25 is engaged with contact 36, applicant's system is in position to function. Upon closure of switch 17, normal ringing current, which is composed of a series of pulses, is supplied by ringing generator 16 through circuit 15, conductor 21, switch 25, contact 36, conde-

tors 30 and 29 to relay 28, and then through conductor 31, condenser 32, conductor 35, line 22, and circuit 15, back to ringing generator 16.

As is well known, there is an indication at the calling telephone when the called telephone is being rung. When relay 28 is in the circuit, this normal indication at the calling end is somewhat modified. The calling party is thus informed that a recording system is available at the called end for the purpose of recording any message which such party may desire to leave. If the calling party wishes to leave a message, a predetermined symbol may be dialed on dial 14 at the calling end. The system may be so arranged either that this automatically causes the additional ringing generator 19 to be brought into the circuit through closure of switch 20, or simply advises an operator at the central exchange 14, that the calling party wishes to leave a message at the called end. In the latter case, the operator at the central exchange would, of course, arrange to close the switch 20.

When normal ringing current is supplied to relay 28 as described above, switch 33 engages contact 38 each time that a pulse of ringing current passes through the relay. Each such engagement closes the circuit through the motor 40 by way of line 81, conductor 26, contact 38, switch 33, conductors 39 and 27, and line 82. Motor 40 operates the gear train in such a way as to cause gear 42 to rotate in a clockwise direction. As a result of the action of spring 46 in tending to restore the gear train to its original position after it has moved from such position, the gear train does not advance sufficiently far, when normal ringing current is supplied to relay 28, to cause switch 49 to engage contact 50.

If, however, switch 20 is closed to cause additional ringing generator 19 to be brought into the circuit in place of ringing generator 16, the pulses of ringing current supplied to relay 28 are longer in duration than when normal ringing current is being supplied. As a result of this modification in ringing current, the gear train is able to advance to a sufficient degree, even against the action of spring 46, to permit dog 83 to move switch 49 into contact with contact 50.

In place of relay 28, motor 40, the gear train and the accompanying circuit connections, which are described above, other means which would be responsive to special but not to normal ringing current could be provided to close switch 49. Such other means could also be so constructed that the special ringing current would differ from the normal ringing current in some way other than in increased duration of the pulses of current.

When switch 49 engages contact 50, a circuit is closed through relay 65 by way of conductors 51, 64 and 66, battery 67, conductor 68, contact 85, switch 69 and conductors 70 and 48. The flow of current through the relay 65 causes switch arm 58 to move into engagement with contacts 52, 53, and 54. Engagement of conducting portion 55 with contact 52 causes the circuit through the switch 49 and contact 50 to be short-circuited and the relay 65 to be maintained in closed position even after switch 49 has opened. Engagement of conducting portion 56 with contact 53 completes a circuit to motor 75, through line 81, conductors 72, 71 and 80, and line 82. Engagement of conducting portion 57 with contact 54 completes a circuit to recorder head 76 through line 22, conductors 35, 79 and 78, contact 54, con-

ducting portion 57, conductors 73 and 30, contact 36, switch 25, and line 21.

Thus, through the closing of relay 65, the recorder is placed in operation to record the message which the calling party wishes to leave. Upon completion of the message, the recorder causes the switch 69 to be momentarily opened. Opening of the switch 69 causes the circuit through the relay 65, and switch arm 58, to be opened, since the other relay closing circuit through switch 49 and contact 50 had already been opened when the supply of ringing current to relay 28 had ended.

The system is thus placed in condition to record a new message.

What is claimed is:

1. A system for recording telephonic messages comprising: a calling telephone; a called telephone; telephone circuit means connecting the two telephones, such telephone circuit means including means for selectively supplying normal or special ringing current to such circuit means; recording means for recording a message passing through the telephone circuit means; additional circuit means for connecting the recording means to the telephone circuit means, such additional circuit means including actuating means for initiating operation of the recording means and thus initiating recording of the message, the actuating means being operated by special but not by normal ringing current to initiate operation of the recording means; the actuating means, when supplied with normal ringing current, also providing a distinctive indication, through the telephone circuit means, of the availability of the recording means, this distinctive indication being different from the normal indication which is provided when the normal ringing current is being supplied to the called telephone.

2. A system for recording telephonic messages comprising a calling telephone, a called telephone, telephone circuit means connecting the two telephones, such telephone circuit means including means for selectively supplying normal or special ringing current to such circuit means, a source of power, a first normally-open relay including a winding which is connected to the telephone circuit means, and also including a first normally-open relay switch, such relay being operated by either normal or special ringing current to close such first switch, recording means including a recorder motor and a recorder head, a second normally-open relay including a winding and a second normally-open relay switch, switch-closing means in series with the source of power and the first relay switch, such switch-closing means including a fourth switch and means for closing such fourth switch when the first relay switch is closed by passage of special ringing current through the winding of the first relay but not when the latter switch is closed by passage of normal ringing current through this winding, first circuit means for connecting the winding of the second relay in series with the fourth switch, with the source of power and with normally-closed means for momentarily opening such first circuit means upon completion of recording of a message, second normally-open circuit means for short-circuiting the fourth switch, third normally-open circuit means for connecting the recorder head to the telephone circuit means to record a message originating at the calling telephone, and fourth normally-open circuit means for connecting the recorder motor to the source of power, the latter three circuit means

including the second relay switch and being open when such switch is open and being closed when such switch is closed.

3. A system for recording telephonic messages, as described in claim 2, in which the special ringing current differs from the normal ringing current in providing pulses of current of longer duration than those of the latter, and in which the means for closing the fourth switch comprise a gear train having a certain original position and capable of closing this switch when driven a pre-determined distance from such original position, means for driving this gear train, the latter means being operated upon closure of the first relay switch, and means for restoring the gear train to its original position when the first relay switch is open and thus the means for driving the gear train are not being operated, such restoring means being so constructed that when normal ringing current is supplied to the first relay winding, the gear train is not permitted to move far enough to close the fourth switch but sufficient movement to close such switch is permitted when special ringing current is supplied to the first relay winding.

4. A system for recording telephonic messages, as described in claim 2, in which the means for momentarily opening the first circuit means upon completion of recording of a message, comprise a normally-closed switch which is opened by the recording means.

5. A system for recording telephonic messages, as described in claim 2, in which the means for momentarily opening the first circuit means upon completion of recording of a message, comprise a normally-closed switch which is opened by the recording means, and in which the special ringing current differs from the normal ringing current in providing pulses of current of longer duration than those of the latter, and in which the means for closing the fourth switch comprise a gear train having a certain original position and capable of closing this switch when driven a pre-determined distance from such original position, means for driving this gear train, the latter means being operated upon closure of the first relay switch, and means for restoring the gear train to its original position when the first relay switch is open and thus the means for driving the gear train are not being operated, such restoring means being so constructed that when normal ringing current is supplied to the first relay winding, the gear train is not permitted to move far enough to close the fourth switch but sufficient movement to close such switch is permitted when special ringing current is supplied to the first relay winding.

6. A system for recording telephonic messages comprising: a calling telephone; a called telephone; telephone circuit means connecting the two telephones, such telephone circuit means including means for selectively supplying normal or special ringing current to such circuit means; recording means for recording a message passing through the telephone circuit means; additional circuit means for connecting the recording means to the telephone circuit means, such additional circuit means including actuating means for initiating operation of the recording means and thus initiating recording of the message, the actuating means being operated by special but not by normal ringing current to initiate operation of the recording means; such additional circuit means also including means for maintaining the recording means in operation and thus

continuing recording of the message, after the supply of special ringing current has ended.

7. A system for recording telephonic messages, as described in claim 6, in which the actuating means, when supplied with normal ringing current, also provide a distinctive indication, through the telephone circuit means, of the availability of the recording means, this distinctive indication being different from the normal indication which is provided when the normal ringing current is being supplied to the called telephone.

8. A system for recording telephonic messages, as described in claim 6, which includes means for disconnecting the recording means from the telephone circuit means when the recording of the message has been completed.

9. A system for recording telephonic messages, as described in claim 6, which includes means for disconnecting the recording means from the telephone circuit means when the recording of the message has been completed, these disconnecting means being operated by the recording means.

10. A system for recording telephonic messages comprising: a calling telephone; a called telephone; telephone circuit means connecting the two telephones, such telephone circuit means including means for selectively supplying normal or special ringing current to such circuit means; recording means; additional circuit means for connecting the recording means to the telephone circuit means, such additional circuit means normally being in open-circuit condition; circuit-closing means responsive, through connection with the telephone circuit means, to special but not to normal ringing current to close the circuit of such additional circuit means, thus connecting such recording means to the telephone circuit means so that such recording means may record a message originating at the calling telephone; such additional circuit means also including means for maintaining the circuit of such additional circuit means in closed condition and thus continuing recording of the message, after the supply of special ringing current has ended.

11. A system for recording telephonic messages, as described in claim 10, in which the circuit-closing means, when supplied with normal ringing current, also provides a distinctive indication, through the telephone circuit means, of the availability of the recording means, this distinctive indication being different from the normal indication which is provided when the normal ringing current is being supplied to the called telephone.

12. A system for recording telephonic messages, as described in claim 10, which includes means for disconnecting the recording means from the telephone circuit means when the recording of the message has been completed.

13. A system for recording telephonic messages comprising: a calling telephone which includes a transmitter; a called telephone; telephone circuit means connecting the two telephones, such telephone circuit means including means for selectively supplying normal or special ringing current to such circuit means; recording means for recording a message delivered to the transmitter of the calling telephone; additional circuit means for connecting the recording means to the telephone circuit means, such additional circuit means including actuating means for initiating operation of the recording means and thus initiating recording of the message, the actuating means being operated by special but not by normal ringing current to initiate operation of the

recording means; such additional circuit means also including means for maintaining the recording means in operation and thus continuing recording of the message, after the supply of special ringing current has ended.

14. A system for recording telephonic messages, as described in claim 13, in which the actuating means, when supplied with normal ringing current, also provide a distinctive indication to the calling telephone of the availability of the recording means, this distinctive indication being different from the normal indication which is provided when the normal ringing current is being supplied to the called telephone.

15. A system for recording telephonic messages, as described in claim 13, which includes means

for disconnecting the recording means from the telephone circuit means when the recording of the message has been completed.
